UNITED STATES PATENT OFFICE.

EDWIN E. SLICK, OF PITTSBURGH, PENNSYLVANIA.

MACHINE FOR ROLLING.

1,423,268.

Specification of Letters Patent. Patented July 18, 1922.

Application filed November 29, 1919. Serial No. 341,390.

To all whom it may concern:

Be it known that I, EDWIN E. SLICK, a citizen of the United States, residing at Pittsburgh, in the county of Allegheny and

5 State of Pennsylvania, have invented a new and useful Improvement in Machines for Rolling, of which the following is a full, clear, and exact description, reference being had to the accompanying drawings, 10 forming part of this specification, in which—

Figure 1 is a plan view of a machine embodying the invention;

Figure 2 is a side elevation taken partly 15 in section;

Figure 2^a is a plan view of the nested rollers and cage;

Figure 3 is a vertical central section through the parts which engage the work;

20 Figures 4, 5 and 6 are sections similar to Figure 3 but illustrating three modifications respectively.

The present invention relates to machines for rolling and particularly to a machine 25 having a roller or rollers pressed against the work, so arranged to efficiently roll out the blank being operated upon. The roller or rollers are preferably mounted in a cage to keep them in proper position, and in 30 alignment when more than one roller is used.

In machines of this character it is advantageous to use rollers of small diameter because the thrust against the work is concentrated in a smaller area than when a roller of larger diameter is used. Moreover, it is desirable to use solid rollers. The employment of a cage for positioning the rollers permits small rollers to be used 40 and permits such rollers to be solid, since it is not necessary to bore them for any supporting or aligning shaft. In the illustrated embodiment of the invention the work is carried on a work support, illustrated as a supporting plate, and the blank is rolled out and thinned by means of a series of small rollers which are pressed against the work by means of a thrust member, illustrated as a thrust plate, the thrust member and work support being relatively movable so that the rollers are caused to travel over the surface of the work in rolling contact therewith.

Other features of the invention relate to 55 certain arrangements and combinations of

parts hereinafter described and more particularly pointed out in the claims, the advantages of which will be apparent to one skilled in this art from the following description:

Referring to the embodiment of the invention illustrated in Figures 1 to 3 of the drawings, the work, which is illustrated as a previously heated flat plate or sheet metal disk, is carried on a work support 2. 60 This work support is dished as shown in Figures 2 and 3, so as to give the proper taper or shape to the finished work, the work being tapered from the center to the periphery. The blank is rolled into the 65 tapered sheet by means of a plurality of rollers 3 pressed against the work by a thrust plate 4, which is rotated relatively to the work support 2. The rollers 3, are loosely mounted in a cage indicated generally by reference numeral 5. This cage comprises two semi-circular blocks 6, the inner edges of which are concave to fit around and guide the rollers 3. A band 7 fits around the two blocks 6 and holds 70 them together. The thrust plate 4 is mounted on a rotating head 8, and is made of hardened steel to withstand the wear from the rollers. The thrust plate 4 and cage 5 are held on the head 8 by means of 75 rings 9 and 10, which are supported on the head 8 by means of bolts 11. The ring 9 has countersunk bolt holes for the flanges 12 on the bolts which support it. Threaded on the lower ends of the bolts 11 are nuts 80 13 which support the ring 10. By removing the nuts 13, the ring 10 can be taken off and the cage 5 released. Then, if it is desired to take off the work plate 3, it can be taken off by loosening the nuts 13^a. 85

A centering stud 15 centers the work plate 4 on the head 8 and a pin 16 holds the work plate and head against relative rotation. The cage 5 is held so that it can freely rotate in its supporting ring 10. 90 Sufficient clearance is provided between the cage 5 and the work so that the cage may turn freely relative thereto.

The work supporting plate 2 is made of hardened steel or cast chilled iron and is 105 supported on a head 17. It is centered on the head by means of a hollow stud 18 and is prevented from rotating relatively to the head 18 by means of a pin 19. A spring pressed stud 20 projects through the work 110

support 2 and into the hole drilled in the center of the disk for the purpose of centering the disk on the work support.

The blank to be operated upon may be a flat plate or sheet metal disk with a hole bored through it to receive the stud 20. The disk is of uniform gauge and is smaller in diameter than the completed tapered disk into which it is rolled. The blank may, 10 however, be of shapes other than circular, for example, it might be square. Moreover, it need not necessarily be drilled for the stud 20 but may be solid, in which case the centering stud is unnecessary. During the 15 rolling operation, the two heads 8 and 17 are thrust against each other under pressure and are relatively rotated so that the rollers 3 roll around and over the top of the work. The completed blank after it is rolled is indicated by reference numeral 25 in Figure 3. The rollers 3 are loosely mounted in the cage and are frictionally driven by contact with the relatively moving thrust plate 4 and the blank 25. 20

As shown particularly in Figure 2, the rollers at each side of the axis of rotation, are so spaced that the rollers at one side will not track with the rollers on the other side. This prevents ridges from being rolled in 25 the work at points between the separate rollers. As shown in Figure 2, the two series of rollers on opposite sides of the center are separated by spacers 26 formed on the blocks 30 of the roller supporting cage. These spacer blocks 26 are a little to one side of the axis of rotation. As shown in Figure 2, there are nine rollers at the left of the axis of rotation and eight at the right. This arrangement insures that the radius from the axis of rotation to the point of separation between two rollers at one side of the center is equal to the radius from the axis of rotation to the middle of a roller on the opposite side, this, 35 as heretofore explained, preventing the rollers from tracking and forming ridges in the work. As shown in Figures 2 and 2^a the end faces of the rollers 3 are slightly bulged at the center, this bulging being somewhat exaggerated in the drawing for the purpose 40 of illustration. The rollers therefore come in end to end contact only at their centers, so that there is substantially no friction between adjacent rollers. Thus each roller is permitted to assume its own speed and is not 45 subjected to frictional drag by an adjacent roller which is moving slower or faster.

It is found to be advantageous in work of this character to employ rollers of small diameter, on account of their smaller surface of rolling contact with the work. Therefore, the thrust of the rollers against the work is concentrated in a smaller area and the work rolled out more efficiently than would be the case if larger diameter rollers 60 were used. Since the rollers 3 are subjected

to a considerable thrust, it is desirable that they be made solid. The use of the cage 6 permits small solid rolls to be used. The cage holds the rollers in alignment and prevents any roller from moving sidewise out of its end to end alignment with the other rollers. With the cage it is unnecessary to bore the rolls to receive any shaft for holding them in alignment or supporting them, thus permitting the rolls to be made solid and of 70 a maximum strength.

The head 8 is mounted in the cross pedestal of the machine so as to rotate. As shown in Figure 2, the head 8 is provided with a vertical shaft 30 extending through a bushed bearing 31 while a work plate 32 forms a vertical thrust bearing for the head 8. The bearings are lubricated through the oil groove 33. Splined to the head of the shaft 30 is a gear 34 which is driven by a 80 pinion 35. The pinion 35 is carried on a shaft 36 which, at its lower end, has a bevel gear 37, driven by a bevel gear 38 on a shaft 39, which is driven through the reduction gearing 40 by electric motor 41.

The head 17, which carries the work support 2, is vertically movable and is forced by hydraulic pressure against the rollers 3. The head 17 has a plunger 45 which enters a hydraulic cylinder 46 supplied with fluid 90 under pressure through a pipe 47. An adjustable collar 48 on plunger 45 limits its upward movement. A pin 51 extends from the head 17 into a stationary part of the machine to prevent the head 17 from rotating. 100

The work piece is placed on the work support 2 and then fluid under pressure is admitted into the hydraulic cylinder so as to force the work support and work up against the rollers 3. The head 8 with the thrust plate 4 are rotated as the work support is moved up under hydraulic pressure, so that the work piece is rolled out under pressure from a disk of uniform gauge into a tapered disk of larger diameter. The blank which is placed on the 105 work support or guide member 2 is of smaller diameter than the tapered disk into which it is rolled.

The action of the rollers on the heated metal blank is to thin the blank and cause 110 the metal to flow radially outward, thus reducing the gauge of the blank but increasing its diameter.

In Figure 4 is illustrated a modified construction in which two sets of rollers are provided for operating on opposite sides of the work piece. In Figure 4 the heads 8 and 17 correspond to the heads 8 and 17 shown in Figure 2. The head 8 has a thrust plate 60 and the head 17 has a thrust plate 120 61. Two sets of rollers 62 and 63 are provided. These are held in cages 64 and 65, the cages being similar in construction to cage 6. The cages 64 and 65 are provided with extensions 66 and 67, which hold the 125 130

cages against rotation. The heads 8 and 17 are rotated in the same direction, the head 8 being driven substantially as shown in Figure 2. The head 17 is provided with 5 a gear 70 by means of which it is rotated. The plunger 45, which extends down from the head 17, has a hydraulic plunger similar to that shown in Figure 2 so that the work may be put under pressure while the heads 10 8 and 17 are rotated. Since the head 8 and its thrust plate 60, and the head 17 and its thrust plate 61 are rotated in the same direction, the two sets of rollers 62 and 63 are driven in the same direction and serve 15 to rotate the blank around between them.

In Figure 5 is shown another modification in which one of the heads 8 and 17 is stationary and the other is rotated. As shown in Figure 5, the head 17 has a work support 80 having a conical upper surface. The head 8 has a thrust plate 81 with a conical lower surface. Two conical rollers 82 and 83 are held in a cage 84 and by the relative rotation of the work support 80 and thrust 20 plate 81, are moved around over the work piece to roll it into a tapered disk. As shown in Figure 5, this disk is not only tapered but is dished, which form of disk is particularly desired in the construction of 25 certain types of automobile wheels.

In Figure 6 is illustrated still another modification in which two work pieces may be operated on by a single set of rollers. As shown in Figure 6, there are two work 30 supports 90 and 91 for the upper and lower work pieces, respectively. Between these two work supports is a cage 92 for guiding the plurality of rollers 93. The cage and rollers are arranged substantially as shown 35 in Figures 2 and 3. The cage 92 is supported on a fixed part of the machine 94 and held against rotation. The two thrust plates 90 and 91 are forced against each 40 other and are rotated at the same speed but 45 in opposite directions.

While the heads 8 and 17 are shown as rotating about a vertical axis, it is obvious that such axis of rotation might be horizontal or inclined if more convenient in the 50 particular machine to be built. While the machine is illustrated as operating upon circular blanks to roll them into tapered disks other work pieces may be used and other shapes rolled. For example, a square blank 55 may be used and a shape rolled from it and the projecting corners trimmed off if desired. Instead of a tapered shape, other things may be rolled and the rolling may be restricted to a more limited annular area 60 than that indicated in the drawings. For example, an annular zone only might be rolled in the work. The invention in its broader aspects is not limited to rolling circular shapes or to rolling annular areas 65 on work pieces, since the general arrange-

ment of a roller or rollers and the supporting or aligning means therefor may be used for other types of rolling apparatus. Instead of the work supporting member and thrust member rotating at right angles to 70 the axis of the roller or rollers, as illustrated in the drawings, other arrangements of work supporting means might be employed, such for example as rollers through which the work is fed with a cage for supporting frictionally driven rollers between them. In other words, the advantage of the present invention, and particularly that feature of the present invention which relates to the employment of comparatively 75 small rollers pressed into rolling contact with the work and properly positioned by means of a cage, may be employed in a wide variety of rolling machines.

The present invention is therefore not 80 limited to its illustrated embodiment but may be otherwise embodied within the scope of the following claims.

By the words "roller system" in my claims, I intend to cover either one roller 90 or a plurality of rollers in the combination claimed.

I claim:

1. In a rolling machine, a work-supporting member and a thrust member, connections arranged to impart relative rotation thereto around a stationary axis, an imperforate system of rolling elements between the members, and a holding device for the system of rolling elements arranged to hold 100 it in fixed relation to the center of rotation, substantially as described.

2. In a rolling machine, a work-supporting member and a thrust member, one of said members being mounted for rotation 105 about a fixed axis, a system of rolling elements between the members arranged to move in circular paths relative to the blank, a cage engaging the exterior of the rolling elements and holding them in the same position relative to the center of rotation, and connections arranged to impart relative rotation about a fixed axis to the said members, substantially as described.

3. In a rolling machine, a work-supporting member and a thrust member, one of said members being mounted for rotation about a fixed axis, a roller system between the members arranged to move in a circular path relative to the blank, a cage engaging 120 the exterior of the roller system to hold it in fixed relation to the cage and the center of rotation, and connections arranged to impart relative rotation about a fixed axis to the thrust member and the work-supporting 125 member, substantially as described.

4. In a rolling machine, a work-supporting member and a thrust member, one of said members being mounted for rotation about a fixed axis, at least two series of roll- 130

ing elements between the members, a cage engaging the exteriors of the two series and holding them in the same relative positions, and connections arranged to impart relative 5 rotation about a fixed axis to the thrust member and the work-supporting member, substantially as described.

5. In a rolling machine, a work-supporting member and a thrust member, connections arranged to impart relative rotation thereto around a fixed axis, a system of substantially imperforate rolling elements between the members, and a cage arranged to hold the rolling elements in the same relative 10 angular positions, substantially as described.

6. In a rolling machine, a work-supporting member and a thrust member, connections arranged to impart relative rotation thereto around a fixed axis, a system of substantially imperforate rolling elements be- 15

tween the members, and a cage arranged to hold the rolling elements in the same relative angular positions, the outer rolling elements being nearer the work-supporting 25 member than the inner rolling elements whereby the blank is tapered towards its periphery, substantially as described.

7. In a rolling machine, a work-supporting member and a thrust member, connections arranged to impart relative rotation thereto around a stationary axis, an imperforate system of rolling elements between the members, a holding device for the system of rolling elements arranged to hold it in 30 fixed relation to the center of rotation, means for forcing the members toward each other, and a stop arranged to limit said movement, substantially as described.

In testimony whereof, I have hereunto set 40 my hand.

EDWIN E. SLICK.
